UNITED STATES PATENT OFFICE.

THOMAS EDGAR CARTER, OF AUCKLAND, NEW ZEALAND.

WINDOW-SASH LIFTING AND LOCKING APPLIANCE.

No. 901,680.

Specification of Letters Patent.

Patented Oct. 20, 1908.

Application filed November 30, 1907. Serial No. 404,600.

To all whom it may concern:

Be it known that I, THOMAS EDGAR CARTER, subject of the King of Great Britain, residing at Auckland, in the Dominion of New Zealand, have invented a new and useful Improvement in Window - Sash Lifting and Locking Appliances; and I do hereby declare the following to be a full, clear, and exact description of the same.

10 This invention relates to means whereby the sashes of windows may be raised and lowered and locked at any height.

The invention has been designed specially for the purpose of dispensing with the usual 15 balancing weights, pulleys, and cords, which are generally a source of trouble through wear and breakage.

The means devised consist in the use of a tooth pinion mounted in the pulley stile of 20 the window, and gearing with the teeth of a rack extending along the adjacent edge of the window sash. The pinion is mounted on a spindle projecting into the room, and is operated by a handle secured upon its end. 25 Combined with the rack are antifriction rollers, which are mounted therein, and run on the face of the pulley stile. On the other edge of the sash, a similar roller is mounted at the bottom, and at the top end, and combined with each roller is a flat spring that 30 bears against the face of the adjacent pulley stile.

Special means are provided whereby the pinion spindle may be prevented from turning so that the sash may be held at any 35 height, and locked from being further opened or closed from the outside.

In the accompanying drawings, which illustrate the invention, Figure 1 is a face view 40 (partly in section) of a window sash and frame provided with the means constituting this invention. Fig. 2 is a detail front view of the means for locking the pinion spindle. Fig. 3 is a side elevation of the frame for carrying the pinion and spindle, showing such parts in position and the locking means. Fig. 4 is a face view of the upper end of the toothed rack attached to the window sash. Fig. 5 is a similar view of one of the antifriction 45 rollers and springs attached to the other edge of the sash.

a is the sash, *b*, *b*, are the pulley stiles.

c is the toothed rack secured along one edge of the sash. *d*, *d*, are the antifriction rollers mounted in bearings formed at each 55 end of this rack, and which are arranged so as to have their peripheries bearing upon the adjacent pulley stile *b*.

e is the toothed pinion that is mounted on the spindle *f*. The spindle is carried in bearings formed in a metal casing *g* that is let into the front of the window frame in such a manner that the pinion will pass through an opening in the stile *b* and its teeth engage with the rack *c* upon the sash. The end of 60 the spindle projects in through the front of the casing *g*, and to it is attached a handle *h* by means of which it may be turned. The inner end of this spindle is formed with a squared portion *j* and secured upon the 65 front face of the casing *g* is a plate *k* which is so held as to be free to slide up and down thereon. This plate is formed with a slot *m* in its lower edge that is adapted to fit on to the squared portion of the spindle, so that 70 when the plate *k* is lowered, the spindle will be prevented from turning.

o, *o*, are the antifriction rollers secured upon the other edge of the sash. These 75 rollers are mounted in plates *p* in such a manner that they will be free to rotate, and will engage with the adjacent stile *b*.

r are the spring plates secured to the plates *p* and each one of which is bowed outwards, as shown, to bear against the pulley 85 stile.

The window will be raised or lowered by rotating the spindle *f*, and may be held and locked at any position by dropping the slotted plate *k* over its squared portion. The 90 antifriction rollers and springs will serve to provide for the sash running freely, and to prevent any jamming or rattling thereof.

What I do claim as my invention, and desire to secure by Letters Patent, is,—

In a window, a toothed rack secured along the edge of a sash frame and having an antifriction roller journaled in each end thereof 95 engaging with the adjacent face of a pulley stile, a metal frame secured within the pulley stile, a spindle carried transversely in such frame and projecting beyond its front 100

end a squared portion upon such projecting end, a sliding plate secured against the front face of the frame, and having a slot adapted to fit on to the squared portion of the spindle, 5 and a pinion mounted upon the spindle and engaging with the rack on the sash, substantially as specified.

In testimony whereof, I have signed this specification in the presence of two subscribing witnesses.

THOMAS EDGAR CARTER.
